SPINNING-ROTOR FOR MAKING MINERAL WOOL AND THE LIKE

Richard M. Downey, North Judson, Ind., assignor to United States Gypsum Company, Chicago, Ill., a corporation of Illinois

Application November 1, 1951, Serial No. 254,376

5 Claims. (Cl. 18—2.6)

The present invention relates to an improved rotor for centrifugally spinning a molten material into fibers, so as to produce mineral wool, glass wool, and the like.

In the making of fibers of mineral matter, it has already been proposed to employ rapidly rotating spinners which hurl molten viscous material into space with sufficient velocity to produce fibers therefrom. A number of different types of such spinners have been developed in the past. They may be roughly classified into three distinct types:

(1) Where a horizontal disc is rotated about a vertical axis, with the molten material being allowed to flow onto the disc, being flung into space from the periphery of the disc. This obviously hurls the fibers in all directions, in a plane substantially normal to the axis of rotation.

(2) Where there is used a disc which rotates upon a horizontal axis, with the melt being projected against its sides. Due to gravitational pull combined with centrifugal force, this will produce a more or less downward projection of the resulting fibers.

(3) An inclined roller or spinner is used, onto the grooved edge of which the melted material is allowed to fall. Usually two adjacent rotors or spinners of this type are used.

(4) A cylindrical spinner which rotates upon a horizontal axis, the molten material being allowed to fall upon the cylindrical surface, from whence it is dispersed almost immediately, being flung tangentially outward.

The present invention comprises a spinner which is a compromise between a cylindrical spinner and a disc operating upon a horizontal axis. It comprises one or more closely adjacent spinner elements each having a section like a deep V, with the interior sloping wall serrated so as to form a series of steps, each step or ledge, however, being rather narrow. The molten material is allowed to fall into the V-shaped groove, and, as a result of the rapid revolution of the spinner, is thrown tangentially outwardly from the steps of the sides of the groove with sufficient velocity to draw the molten material out into fibers, which, as a result of the cooling by friction against the air, become solidified into fine fibers of mineral wool or the like, depending upon the nature of the molten material. The temperature and viscosity of the molten material must be closely controlled so as to obtain fibers of the desired degree of fineness and length. As the present invention is primarily directed to the apparatus rather than to the details of its operation, no particular attention need be paid to the exact conditions of operation, except in so far as it may be stated that the temperature of the melt, for example, in the case of slag, may be from about 2500° F. to about 3000° F., and the speed of rotation at a melt rate of about 500 pounds per hour per disc, may be from about 7500 to 16,000 feet per minute. For a 16" disc, this corresponds to about 1800 to 3800 R. P. M.

The present invention is illustrated in drawings filed concurrently herewith, in which

Fig. 1 is a front elevational view;

Fig. 2 is a side elevational view;

Fig. 3 is a top plan view;

Fig. 4 is a vertical section through one of the individual spinner elements along line 4—4 of Fig. 1, on an enlarged scale; and

Fig. 5 is a section of one-half of one of the individual spinners, on a still further enlarged scale.

The rotatory element which serves to transform the molten mineral-wool-forming material into fibers actual-

2

ly comprises an assembly of individual spinners, each of which has a deep V-shaped groove. These spinners are assembled on a horizontally extending shaft to form a set of the desired number of spinners—for example, ten of them. The apparatus also comprises a frame and a suitable prime mover, such as a motor, and is mounted on a frame which rides, by means of flanged wheels, on a track so that it may be moved in and out of position relative to the source of molten material.

Referring now to Fig. 1, the apparatus comprises two rails 5 and 6 upon which ride the wheels 7 and 8 which are suitably supported on a shaft 9. Bearings 10 and 11 serve to journal the shaft, and to these bearings there are secured flanged supports 12 and 13 which serve to support the stanchions 14, 15, and 16, which in turn support the actual fiberizing instrumentation. The latter comprises two bearings 17 and 18 which are supported on the stanchions 15 and 16, respectively, by the intermediate supports 19. Passing through the said bearings 18 and 17 is a shaft 20 to which there is affixed a collar 21, to which in turn there are keyed a plurality of the actual spinning elements 22, of which there are, in the modification shown, ten. The shaft 20 is coupled by means of the coupling 23 to the shaft 24 of a suitable prime mover which is broadly designated by the reference numeral 25, and which may be an electrical motor, gear box, or the like—an electric motor, however, being preferred. The electrical connections are not shown as they are not a part of the present invention.

30 The said prime mover 25 is supported directly upon the stanchions 14, being secured thereto by the usual type of flanges and bolts 26 and 27.

As can best be seen in the side elevational view in Fig. 2, there are also provided a deflection shield 28 and a diagonally upwardly rising supporting beam 29 which lend rigidity to the entire structure. As aforementioned, the entire carriage rides on the wheels 7 and 8, there being two sets of these, the side wheels 7 and 7' only being visible in Fig. 2.

40 In order to prevent the device from moving on the rails when it is in the desired position, clamping means are provided adjacent the wheels consisting of angularly bent metal pieces 30 and 31 which have an inwardly extending flange 32 and 33, there being corresponding shorter flanges 34 which are directed oppositely thereof. The flanges 32, 33, and 34 lie directly underneath the head of the rails 5 and 6 respectively. By means of the bolts 35, flanges 30 and 31 may be forced against the rail heads so that the apparatus will not be capable of being moved until the bolts 35 are loosened, whereafter it is possible, manually or otherwise, to wheel the apparatus on the rails 5 and 6. The said angular metal pieces or plates 30 are secured to the carriage by means of bolts 36 and 37. Not connected with the apparatus itself, but serving to feed the same, there is diagrammatically illustrated in Fig. 2, and positioned almost directly above the spinner element 22, a trough 38 which serves to supply the material which is to be fiberized to the rotor elements 22. It should be understood that the lower edge 39 of the trough 38 is suitably lipped or cut away so as to supply individual streams of molten material to each of the spinning elements 22, so that there will be, for instance, eight streams of molten material falling into the grooves of the spinner elements 22. The two outermost elements do not receive any molten material, but serve as heat-flingers to cool the apparatus.

45 For a better understanding of the nature of these spinning elements, reference is directed to Figs. 4 and 5. It will be seen that the spinner elements 22 are substantially of the shape shown having the deep circumferential grooves 40. The sides of these grooves extend downwardly obliquely, although they do not actually meet there being a bottom 41 in each of the spinning element 22. The sides of these elements, as can best be seen from the still further enlarged view in Fig. 5, are serrated by being cut into the form of a very large number of individual steps 42, which therefore have a rise component and a step or tread component. This is quite important and greatly contributes to the efficiency of the apparatus. As the molten material contacts the serrations, its downward flow will be retarded and the

steps will fill up with the material, a small amount of which will adhere to the metallic surfaces of the spinner. The result is that when the major portion of the molten material is centrifugally tangentially discharged, the individual streamlets thus produced will still be anchored at one end to the adhering film so that they will be drawn out and become sufficiently attenuated eventually to break off in the form of the desired type of fibers. If the surface of the spinner were smooth, there would not be afforded a sufficient amount of adhesion, and the formation of the desired thin adherent film would not take place. The particular advantage of having two opposed sides inclined toward each other is to take care of the possible wobbling of the stream so that it is assured of being caught upon either side of the serrated surfaces of the individual spinners. There is usually but little of any of the molten material which will reach the bottom 41 of the groove 40. Moreover, it is the intention that the actual spinning take place from points along the sides of the spinners where the peripheral speed is high enough to cause the formation of fibers of the desired length and fineness, as obviously the peripheral speed is less as the axis of rotation is approached.

Another important feature of the spinners is the provision of the depressions or cutaway portions 44 at both sides of the individual spinners. As the spinners rotate, considerable turbulence is induced in the air along the sides of the spinners because of the presence of these depressions, and this serves to cool the spinners by thus dissipating heat. That is also why the two terminal spinners may thus be used as "heat-flingers" as already indicated, which prevents undue overheating of the bearings upon which the shaft 20 is mounted.

The apparatus operates in the following manner:

The shaft 20 and the collar 21 which is keyed thereto, and also the spinning elements 22, which are in turn keyed to the collar, for example by means of the keys 43, are rapidly rotated at about 2800 R. P. M. by means of the prime mover 25. A suitable molten material, which may be molten slag or a special melt in the nature of glass or a molten rock such as is used in making rock wool, and at a temperature of about from 2500° to about 3000° F., in the case of slag, is allowed to flow into the individual grooves 40 of the spinner elements 22. As the material tends to flow by gravity downwardly toward the bottoms 41 of the grooves 40, the slag or the molten material will cascade downwardly, but before it gets very far, the momentum imparted to it as a result of the rotation of the spinning elements 22 will hurl it off into space in a direction away from the point of impingement of the molten material.

As a small amount of it may be carried almost around the rotor, and to protect the person who is operating the device from being harmed by particles of hot slag which might be rearwardly projected, the aforementioned screen 28 is provided.

When getting ready to operate the device, it is wheeled into the desired position beneath the lip 39 of the trough 38 and the apparatus is set in motion, care being taken to clamp the braking members, which consist of the plates 30, against the rail so there will be no tendency for the apparatus to become displaced relative to its position beneath the edge of the trough 38.

Whenever it is desired to clean this apparatus, or to repair the rotors and spinning elements 22, the bolts 35 may be loosened so that the apparatus may be withdrawn to a position in which it can be conveniently serviced.

It will, of course, be obvious that the prime mover 25 can be replaced by any mechanical equipment, such as pulleys and belting or gear trains and the like, as the essential novelty of the apparatus is primarily directed to the spinning elements themselves and their unique shape, and particularly the provisions of the serrations or steps 42 and the lateral depressions 44. The entire apparatus may be constructed of steel, although it has been found advisable to make the rotors or spinning elements 22 out of stainless steel or some other form of alloy which is resistant to temperatures up to 3000° F. and beyond without distortion or oxidation.

Steel alloys are now known which will withstand the impact of a contact with molten slag without material deterioration, but it is within contemplation of the inventors to make the rotors out of ceramic material or in

fact anything which will withstand the temperature and friction.

The present apparatus has been found to yield fine long filaments of mineral wool and the like which can be directly collected by suitable means such as are known in the art, but it will be considered within the scope of the present invention to provide a suitable gaseous carrier medium which will transport or blow the resulting fibers into a collecting chamber or onto a belt or other means for receiving fibers. As such means are thoroughly well known in the art, they require no illustration.

The particular advantages which reside in the present apparatus lie primarily in the presence of the steps or serrations in the V-shaped groove and the lateral depressions 44. During the operation it will, of course, be obvious that a stream of material will be falling toward the bottom 41 of the individual spinning elements. It is a well known thing, however, that a falling mass of such molten material has a tendency to wobble from side to side so that it is most likely to hit one side or the other. Moreover, the width of the stream is usually greater in diameter than the width of the bottom 41, with the result that the falling stream is intercepted by a large number of sharp edges, namely, the lines where the risers or steps of the serrations meet. Each step, in effect, constitutes a rapidly rotating edge of a disc, that is to say, a cylindrical surface, while the sides or risers represent a vertically spinning disc. Therefore, the material which impinges upon the steps, as well as that which flows down the risers, will be hurled outwardly so as to impart the necessary momentum to the molten material to attenuate it into fibers.

I claim:

1. Apparatus for spinning molten material into fibers which comprises means for melting a material and discharging streams thereof against the sides of discs secured to a shaft mounted for rotation about a horizontal axis, said discs having deep circumferential grooves substantially V-shaped in cross section and with their inner sides serrated by means of a large number of individual steps.

2. Apparatus for spinning molten material into fibers which comprises a supporting frame, two bearings supported on said frame, a shaft rotatably supported in said bearings, individual spinners mounted upon and keyed to said shaft for rotation therewith; said spinners being in the form of discs each having a deep circumferential groove V-shaped in cross section and provided with stepped serrations on its inner walls, means, also mounted on said frame, for rapidly rotating said shaft, a protective shield mounted behind said discs and secured to said frame and means for directing streams of molten material into said groove.

3. A spinning device for producing fibers from molten material by centrifugal dispersion comprising a disc-like body provided with a deep circumferential groove the inner sides of which are provided with step-like serrations, and means for directing streams of molten material into said groove.

4. An apparatus for producing fibers from molten material comprising a plurality of discs as covered by claim 3 all mounted for simultaneous rotation upon a horizontally extending shaft.

5. Apparatus for spinning molten material into fibers which comprises a shaft mounted for rotation upon a horizontal axis, means for rotating said shaft, a plurality of discs mounted on said shaft and keyed thereto for rotation therewith, said discs having sides provided with deep grooves substantially V-shaped in cross section and having the sides of the grooves serrated by means of a large number of individual steps, and means for directing streams of molten material into the grooves on said discs.
